UNITED STATES PATENT OFFICE.

THADDEUS S. BRIGHTWELL, OF BRADDOCK, PENNSYLVANIA.

COIN-CONTROLLED MECHANISM.

Application filed May 21, 1924. Serial No. 714,858.

To all whom it may concern:

Be it known that I, THADDEUS S. BRIGHTWELL, a citizen of the United States, and resident of Braddock, in the county of Allegheny and State of Pennsylvania, have invented certain new and useful Improvements in Coin-Controlled Mechanisms, of which the following is a specification.

This invention relates to liquid dispensing apparatus, and while not limited thereto, relates more particularly to gasoline dispensing apparatus of the coin controlled type.

One object of this invention is to provide a coin controlled mechanism that may be operated in connection with standard gasoline dispensing apparatus which includes a meter, and utilize fluid pressure for forcing the delivery of the gasoline.

Another object of this invention is to provide a novel form of coin control mechanism for controlling the operation of the dispensing apparatus, adapted to permit only a predetermined amount of liquid to be dispensed for each coin deposited.

Another object of the invention is to provide an apparatus having the novel construction, design, and combination of parts hereinafter described and illustrated in the accompanying drawings.

Figure 1 is a front elevation of the assembled device.

Figure 2 is a front elevation of the device, with the front wall removed to show the working parts.

Figure 3 is a sectional elevation through the coin box showing the coin control mechanism.

Figure 4 is a sectional plan on the line IV—IV of Figure 2.

Referring more particularly to the drawings, I have illustrated my invention as applied to the well known and widely used pressure gasoline dispensing stands, which include a casing 2 housing a meter 3 having inlet and outlet conduits 4 and 5, respectively. The meter 3 houses the usual metering mechanism adapted to be operated by the gasoline or other liquid passing therethrough, to rotate a horizontal shaft 6 carrying the usual indicating hand 7 which co-operates with a dial 8 to indicate the quantity of liquid dispensed.

This class of dispensing apparatus, as said before, is of well-known construction

and has gone into wide use, and, therefore, a more detailed description of its construction is not thought necessary, especially since I make no claim of its construction, except as my improvement is combined therewith. 60

Liquid dispensing devices, such as described above, have heretofore been operated or controlled manually by an operator and, therefore, necessitated the constant attendance of an operator. The present invention provides a coin controlled mechanism for controlling the dispensing of the liquid and eliminates the necessity of an attendant, thereby providing an apparatus that may readily be set up for use in districts and locations where it would be unprofitable to maintain an attendant and yet the amount of liquid dispensed would be profitable to the company when no attendant is required. 70

In carrying out my invention I provide a rotary valve 10 in the outlet conduit 5 adapted to control the flow of liquid from the apparatus. The valve 10 is provided with a gear 11 on its stem, which gear is in mesh with a gear 12 on the shaft 6 of the meter mechanism. The ratio of the gears is such that a predetermined quantity of liquid will flow through the meter and be dispensed through the outlet conduit 5 with each revolution or opening and closing of the valve 10. 80

The opening and closing of the valve 10 is controlled by a stop or control lever 14 pivoted intermediate its ends on a suitable support 15 secured to the coin box 16. The forward end of the lever 14 is adapted to engage a stop lug 17 on the gear 11, while the rear end thereof is engaged by a coin, thereby stopping the rotation of the valve 10 and locking the gear 11 and valve 10 against further rotation until said coin is removed. 90

The coin box 16 is positioned to the one side of the casing 2 and is provided with a coin chute or guideway 18, which communicates at its upper end with a slot or opening 19 in the front wall of the casing 2 and extends downwardly to a point adjacent the rear end of the lever 14. The rear end of the lever 14 is cut away to form a concave seat 20 to receive the lower edge of a coin 100 deposited in the chute or guideway 18.

The chute or guideway 18 is provided with flexible or resilient side wall members 21 in the form of very thin leaf springs secured at their upper ends in spaced relation

to the fixed side walls of the guideway, and extending downwardly. The members 21 converge inwardly toward their lower ends and are provided at their lower ends with 5 concave pockets 22 to receive the edges of a coin when it reaches the lower end of the guideway.

In operation a coin is deposited in the opening 19 and passes into the chute or guideway 18. The upper end of the guideway 18 is of such size that the coin will move freely along the guideway for an appreciable distance, then, due to the converged position of the side wall members 21, 10 the coin will engage these members and force them apart and continue its downward movement until it reaches the extreme lower end of the guideway, when it will be received by the pockets 22, which will permit 15 the side wall members 21 to return to their normal position. When the coin is received in the pockets 22 it is held from movement in any direction and, due to the position of the lower end of the guideway 18 over the rear end of the lever 14, the coin will engage the rear end of this lever and hold it in locked position, so that its forward end will be engaged against or in position to engage the stop lug 17 on the gear 14. In 20 order to remove the coin engaged against the rear end of the lever 14, it is necessary to deposit a second coin in the slot or opening 19 and permit it to pass downwardly through the chute or guideway 18 until it 25 engages the upper edge of the first coin. Due to the converged position of the side wall members 21 they will be forced outwardly by the second coin a sufficient distance to release the first named coin from 30 the pockets 22.

After the second coin is deposited in the guideway 18 and has moved the side wall members 21 outwardly to release the first coin from the pockets 22, it is only necessary 35 to move the first coin from the lever 14 in order to permit the operation of the device, and for this purpose I provide a trip lever 25 operated by a plunger 26. The lever 25 is pivoted on a horizontal shaft 27 extending transversely of the chute or guideway 18 and is provided with a horizontal head portion 28 on its upper end adapted to engage and push the coin out of the guideway when the lever is rocked by the 40 plunger 26. The plunger 26 is pivotally engaged with the lower end of the lever 25 and is mounted for reciprocatory movement in a suitable guide 29 secured to the front wall of the coin box 16. A coiled spring 30 is mounted around the plunger 26 and has one end in engagement with the inner end of the guide 29, while its other end is in engagement with a follower 31 on the plunger, so that when the plunger is pressed inwardly to rock the lever 25, the spring 45

will be compressed and when the plunger is released the spring tension will readily return the plunger to normal position.

The head 28 of the trip lever 25 has its forward face offset to provide a projected portion 32 and a shoulder 33. This novel head provides means whereby the plunger 26 and lever 25 must be returned to normal position before the control lever will operate to release the valve 10. In operation, 50 after the second coin has been deposited in the guideway 18, the plunger 26 will be depressed so as to rock the trip lever 25, thereby forcing the portion 32 of the head 28 against the lowermost coin and thus moving said coin out of the chute or guideway 18 and from over the control lever 14 and permitting it to drop into the box 16. As the lowermost coin is moved from over the lever 14 the lever will be rocked about its axis, due to the constant pressure in the meter 3 tending to rotate the gears 11 and 12, and thus causing the stop lug 17 to constantly bear against the forward end of the lever 14. However, due to the offset 55 position of the portion 32 of the head 28, the lever 14 will move up against the shoulder 33 and again be stopped, and in this position the forward end of the lever 14 will not clear the stop lug 17 and, therefore, the valve 10 will not be opened. In order to permit the valve 10 to open, it is necessary to release the plunger 26 and permit it to return to its normal position and thereby allow the lever 14 to rock further 60 around its pivot so as to clear the stop lug 17. The second coin, which is in the guideway when the first one is removed will move downwardly as the first is removed, but due to the raised position of the rear end of the lever 14 this second coin cannot enter the pockets 22 until the lever 14 has cleared the stop lug 17, since the force of the stop lug 17 against the forward end of the lever 14 is greater than the counterweight effect of 65 the coin. However, as soon as the lug 17 is cleared the coin will be of sufficient weight to return the lever 14 to its normal position and, therefore, the coin will move downwardly into the pockets 22 and lock the lever in position to engage the stop lug 17 as it completes a single revolution, thus again stopping the flow of liquid through the outlet conduit 5.

In order to aid the coin to return the lever 14 to its normal or locking position, I may provide a coil spring 35 as shown. However, this is not essential.

While I have shown and described only one specific embodiment of my invention it will be understood that I do not wish to be limited thereto, since various modifications may be made without departing from the scope of my invention as defined in the appended claims.

I claim:—

1. In a coin controlled dispensing apparatus, a control lever fulcrumed intermediate its ends and adapted to be locked against movement by a coin engaging one end thereof, a coin chute adapted to guide coins downwardly against said lever, resilient side wall members along each side of said chute adapted to be pressed outwardly by a coin passing downwardly through said chute, pockets adjacent the lower end of each of said side wall members into which the side edges of the coin project when said coin has reached its lowermost position and rests against said control lever, said pockets being of such depth that a second coin, when deposited in said chute, will move said side wall members outwardly a sufficient distance to release said first coin, and means for moving said first named coin from its position on said control lever, thereby releasing said lever.
2. In a coin controlled dispensing apparatus, a control lever fulcrumed intermediate its ends and adapted to be locked against movement by a coin engaging one end thereof, a coin chute adapted to guide coins downwardly against said lever, resilient side wall members along each side of said chute adapted to be pressed outwardly by a coin passing downwardly through said chute, pockets adjacent the lower end of each of said side wall members into which the side edges of the coin project when said coin has reached its lowermost position and rests against said control lever, said pockets being of such depth that a second coin, when deposited in said chute, will move said side
- wall members outwardly a sufficient distance to release said first coin, and a trip lever adapted to engage and move said first named coin from its position on said control lever, said trip lever being adapted to prevent movement of said control lever until said trip lever is returned to its normal position.
3. In a coin controlled dispensing apparatus, a control lever fulcrumed intermediate its ends and adapted to be locked against movement by a coin engaging one end thereof, a coin chute adapted to guide coins downwardly against said lever, coin controlled means for preventing movement of said coin, said means being releasable by a second coin entering said slot, and means for moving said first named coin from its position on said control lever, thereby releasing said lever.
4. In a coin controlled dispensing apparatus, a control lever fulcrumed intermediate its ends and adapted to be locked against movement by a coin engaging one end thereof, a coin chute adapted to guide coins downwardly against said lever, coin controlled means for preventing movement of said coin, said means being releasable by a second coin entering said chute, and a manually operated trip lever adapted to engage and move said first named coin from its position on said control lever, said trip lever being adapted to prevent movement of said control lever until said trip lever is returned to its normal position.

In testimony whereof I have hereunto signed my name.

THADDEUS S. BRIGHTWELL.
